INTERCHANGEABLE BUCK

Ole H. Langen, Minneapolis, Minn., assignor to The Uni-
press Company, Incorporated, Minneapolis, Minn., a
corporation of Minnesota

Application April 13, 1953, Serial No. 348,447

2 Claims. (Cl. 38—66)

This invention relates to new and useful improvements in bucks for power driven pressing machines of the kind used for pressing garments such as trousers, jackets, coats, smocks, or the like. It particularly relates to new and useful improvements in interchangeable bucks for this type of pressing machine. In this type of pressing machine, a portion of a garment is pressed by positioning the section of the garment desired to be pressed on a slender form or "buck" whereupon a longitudinal portion of the garment is pressed by bringing a presser head down smartly against the buck.

A primary difficulty with such presses of the prior art has been due to the fact that the longitudinal spatulate form or buck, while adapted for pressing a certain type of garment section, has not been readily interchangeable with bucks of other configuration, thus limiting the versatility of such presses.

It is therefore an object of this invention to provide an improved buck structure wherein a plurality of forms may be readily interchanged for pressing various surfaces;

It is still a further object of this invention to provide a means in a power driven pressing machine wherein the basic supporting form may be utilized with a plurality of different adaptors for presenting pressing surfaces of adjustable configuration;

It is still a further object of this invention to provide a stationary form containing a steam chest upon which a plurality of buck pressing surfaces may be positioned;

It is still a further object of this invention to provide a new and useful interchangeable buck pressing surface having novel means for securing the buck padding and cover thereon;

Still further objects of this invention reside in the provision of a supporting form and adaptable covering plates therefor whereupon a plurality of buck forms may be utilized with a single pressing head;

Still a further object of this invention is the provision of an overlay pressing form having unique stiffening means for positioning upon a support.

Other and further objects of this invention reside in the specific constructional details of the interchangeable buck surfaces including the stiffening webs, arcuate configuration and cover securing flange and in the means for securing the cover thereto;

Still further objects of this invention are those inherent and apparent in the apparatus as described, pictured and claimed.

This invention will be described with reference to the drawings in which corresponding numerals refer to the same parts and in which:

Figure 1 is an elevational view of a pressing machine including the buck of the instant invention;

Figure 2 is a plan view of one form of buck casting of the instant invention;

Figure 3 is a diagrammatic plan view of a pressing head for cooperation with the buck casting of Figure 2;

2

Figure 4 is a view of one form of interchangeable buck for the casting of Figure 2;

Figure 5 is a plan view of a second form of interchangeable buck for the casting of Figure 2;

5 Figure 6 is a vertical sectional view taken along the line and in the direction of the arrows 6—6 of Figure 4 and showing in dotted lines the pressing head of Figure 3 in cooperating engagement with said buck;

10 Figure 7 is a sectional view similar to Figure 6 but taken along the line and in the direction of the arrows 7—7 of Figure 5;

15 Figure 8 is an enlarged fragmentary sectional view of a flanged edge of the buck of Figures 6 and 7 and showing a modified manner of attaching the padded covering thereto;

Figure 9 is an isometric view of the cover adapting clip shown in Figure 8;

20 Figure 10 is a top plan view of a modified form of buck casting, modified form of buck and illustrating the outline of a pressing head for cooperation therewith;

Figure 11 is a view similar to Figure 10 but showing a third form of buck casting and adaptor;

25 Figure 12 is a vertical sectional view taken along the line and in the direction of the arrows 12—12 of Figure 10; and

Figure 13 is a vertical sectional view taken along the line and in the direction of the arrows 13—13 of Figure 11.

30 Referring now to the drawings and specifically to Figure 1, there is illustrated a power driven pressing machine generally designated 10 comprising a supporting frame 11 and a pressing head carrying frame 12. Frame 12 is pivoted at 13 relative to supporting frame 11 and is adapted to move from the position of Figure 1 to a position wherein the head is in contact with the buck generally designated 14.

35 The buck 14 comprises a longitudinal support 15 having web reinforcing portions 16 at each end thereof. The support 15 is attached to the frame 11 by any suitable manner, usually being bolted thereto.

Positioned on the buck support 15 is the buck casting 17 which is of the configuration shown in Figures 2, 4 and 5. The casting is provided with a hollow steam chest 18, an arcuate upper surface 19 and a peripheral flange 20. The casting 17 may be formed integral with longitudinal support 15 or formed separate therefrom and connected thereto in any conventional manner.

40 Positioned on the casting 17 is the adapter generally designated 22. Adapter 22 comprises an arcuate padding supporting surface 23 and a depending flange 24. The arcuate supporting surface 23 provides the outline for the buck 14 as shown in Figure 4. The peripheral flange 24 may be formed integral with the supporting surface 23, but in the embodiment shown in Figure 6, has been formed separately therefrom and braized thereto.

45 Positioned upon the arcuate surface 23 is the buck padding 26 over which is placed the buck cover 28. Cover 28 is roughly of the configuration of the supporting surface 23, but slightly larger than this surface so that the edge 29 may extend down along flange 24, as shown best in Figure 8. It may be turned under flange 24 and secured thereto by a plurality of U-clips 30 having snag teeth 31 as shown in Figures 8 and 9. In this instance clips 30 are resiliently positioned over the flange 24 and the upturned edge so as to provide a plurality of retainers for the buck cover around the periphery of adapter 22. Or, as shown in Figures 6 and 7, cover 28

50 may be provided around its edge with a bead 25 which is adapted to be caught under a plurality of hook clips 70

31A positioned on the exterior of flange 24 by suitable means.

As shown in Figure 6, the pressing head 32 is provided with an arcuate surface 33 which cooperates with the arcuate surface formed by the buck cover 28 and follows the contour of adapter 22. The pressing head is also provided with the conventional steam chest 34.

Referring now specifically to the form of adapter 22 shown in Figure 4, it will be seen that the buck casting 17 as shown by the dotted lines in Figure 4 is generally of the contour of the adapter 22. However, depending flange 24 of adapter 22 which abuts the peripheral flange 20 of casting 17 throughout the major portion thereof, is spaced away therefrom at 35 and 36 to give a rounded contour to the pressing surface. The adapter 22 is prevented from movement relative to casting 17 by the peripheral flange 24.

In the form of the adapter 40 shown in Figure 5, the peripheral flange 24 likewise is spaced away from flange 20 not only at 35 and 36 but also at 38 and at 39. Thus, the form of adapter 40 for Figure 5 provides a substantially oval pressing surface whereas the form of adapter 22 in Figure 4 provides a kidney shaped surface.

The pressing head 32 of Figure 3 has a roughly rectangular shape as shown with truncated portions 32A and 32B adjacent the carrying frame 12 (see Figures 1 and 3). Thus the head 32 is movable into and out of engagement with buck 14 and for cooperation with other adapters 22 or 40 for the pressing of various garments, etc.

Thus, either of the forms 22 or 40 may be interchangeably mounted upon buck casting 17 and held in position thereon by the cooperation of flange 20. It may be noted with reference to Figure 5 that a spacer block 41 is provided immovably to position the adapter 40 relative to casting 17 at the point where edge 38 is spaced away therefrom. The spacer block 41 has a depending web 42 which abuts flange 20 as shown best in Figure 7. It may be noted that flange 20 is diminished in extent at portion 43 of the kidney shaped buck casting 17 as shown in Figure 6.

Referring now to the modification 50 of the buck casting shown in Figure 10 and the modification 51 of the adapter for cooperation therewith, it will be understood that the operation is substantially the same as the modification shown in Figures 1-7. In the modification shown in Figure 10, the buck casting 50 is an elongated substantially triangular member and the arcuate buck 51 is rectangular. A plurality of depending stiffening gussets 52, 53, 54 and 55 is provided to fixedly position the adapter 51 relative to the casting 50.

Likewise, as shown in Figure 10, the pressing head 58 utilized for cooperation with buck 51 of that figure is substantially rectangular. As shown with reference to Figures 11 and 13, the rectangular pressing head 58 may likewise be used with a substantially triangular adapter 59. Adapter 59 is spaced only slightly away from the triangular buck casting 50 and is positioned relative thereto by a plurality of relatively small lugs 61.

Thus, it will be seen that with reference to the modification shown in Figures 1-7, there is provided a somewhat rectangular pressing head which is adapted for cooperation with an oval or a kidney-shaped adapter, each of which is interchangeably positioned upon a kidney-shaped buck casting 17 having a lower steam chest 18 therein. The pressing head 32 is conventional and is provided with an upper steam chest 34.

In the modification shown in Figures 10-13, the buck

casting is a triangular casting 50 upon which is supported either a rectangular adapter 51 or a substantially triangular adapter 59. If it is desired to interchange the adapter 59 with adapter 51, adapter 51 is merely lifted off casting 50 and adapter 59 dropped in position thereon as shown in Figures 11 and 13, while the pressing head is in the position shown in Figure 1. An arcuate cooperating surface of the buck cooperates with the arcuate supporting surface of the casting to provide a means of heat transferal to the buck pad and cover.

In the modification shown in Figures 1-7, the buck casting 17 is of the shape shown in Figure 3. Upon casting 17 is supported either a kidney-shaped adapter 22 or an oval-shaped adapter 40. When it is desired to interchange the adapter 22 with the adapter 40 adapter 22 is merely lifted off casting 17 and adapter 40 dropped in position thereon as shown in Figures 5 and 7. It will be maintained in position by the cooperating engagement of peripheral flange 24 with the extending flange 20 of the buck casting.

It is, of course, to be understood, in cooperation with this invention that other shapes of removable adapters may be provided as well as other shapes of buck castings without departing from the spirit and scope thereof.

As many apparently widely differing embodiments of this invention may be made without departing from the spirit and scope thereof, it is to be understood that I do not limit myself specifically to the embodiments disclosed herein.

What I claim is:

1. A pressing machine having thereon a frame, a buck on the frame having a heated upper buck surface of a certain shape and size defined by the peripheral edge of said surface, said buck surface being adapted to serve as a support for any one of a plurality of differently shaped removable buck pads adapted to cover the buck surface, a plurality of differently shaped buck pads each shaped to cover the buck surface and to have portions thereof extending beyond the peripheral edge of said buck surface, each of said pads having a resilient padding on its upper surface and an undersurface fitted complementary to the buck surface so that heat from the buck is conducted to the pad, each of said pads having downwardly extending tabs on the underside thereof arranged to contact spaced opposed portions of the buck along several axes of the buck to removably secure the pad and hold it from displacement on the buck, a pressure arm having a presser head thereon said arm being pivotally mounted on the frame for movement of the presser head into and out of engagement with the buck pad, the shape and size of said presser head being such that it completely covers each of the removable buck pads placed on the buck.

2. The pressing machine specified in claim 1 further characterized in that said tabs are shaped to extend substantially to the edge of the pad to form a stiffening reinforcement for those portions of the pad which extend beyond the peripheral edge of the buck.
